The ornamental design for a male connector, as shown and described.

DESCRIPTION

FIG. 1 is an isometric view of the male connector showing my new invention;

FIG. 2 is an isometric view, from a reverse orientation, of the male connector shown in FIG. 1;

FIG. 3 is a top view of the male connector of FIGS. 1-2; and, FIG. 4 is a side elevation of the male connector of FIGS. 1-3. The broken lines in the drawings illustrate portions of the male connector and form no part of the claimed design.
